UNITED STATES PATENT OFFICE.

FREDRICK W. BROCKSIEPER, OF NEW HAVEN, CONNECTICUT, ASSIGNOR
TO SARGENT & CO., OF SAME PLACE.

DESIGN FOR COFFIN-HANDLE SOCKETS.

SPECIFICATION forming part of Design No. 11,807, dated June 8, 1880.

Application filed May 10, 1880. Term of patent 14 years.

To all whom it may concern:

Be it known that I, FREDK. W. BROCKSIEPER, of New Haven, in the county of New Haven and State of Connecticut, have invented 5 a new Design for Coffin-Handle Sockets; and I do hereby declare the following, when taken in connection with the accompanying drawing and the letters of reference marked thereon, to be a full, clear, and exact description of the 10 same, and which said drawing constitutes part of this specification, and represents a face view.

This invention relates to a design for that part of the coffin-handle by which the handle is secured to the coffin, and commonly called 15 the "socket;" and it consists in the configuration and ornamentation, as shown in the accompanying illustration, and hereinafter described.

The base of the socket is in the form of a 20 Greek cross. A square frame is represented as lying on this cross, the angles of the frame projecting beyond each arm of the cross, and

from the angles of the frame-arms extend inward toward the center, and so as to form an apparent seat for the socket A, portions of the 25 cross being exposed within the frame and between the arms. As shown, the angles of the cross are represented with a rectangular block, a, introduced therein; but these may be omitted. 30

I claim—

The design for coffin-handle socket, consisting of the Greek-cross-shaped base, with the representation of a square frame resting thereon, the angles of the frame at the arms of the 35 cross, and an arm extending from each angle of the frame inward toward the center, and on which the socket proper appears to rest, as described, and shown in the accompanying illustration.

FREDRICK W. BROCKSIEPER.
